UNITED STATES PATENT OFFICE.

EDWARD M. HEWLETT, OF SCHENECTADY, NEW YORK, ASSIGNOR TO GENERAL ELECTRIC COMPANY, A CORPORATION OF NEW YORK.

MEANS FOR CONTROLLING VALVES OR OTHER MOVABLE DEVICES FROM A DISTANT STATION.

No. 843,814.

Specification of Letters Patent.

Patented Feb. 12, 1907.

Application filed May 29, 1906. Serial No. 319,306.

To all whom it may concern:

Be it known that I, EDWARD M. HEWLETT, a citizen of the United States, residing at Schenectady, county of Schenectady, State 5 of New York, have invented certain new and useful Improvements in Means for Controlling Valves or other Movable Devices from a Distant Station, of which the following is a specification.

10 The present invention relates to means for controlling electric motors, and particularly motors adapted to operate a valve or other device arranged to be movable within defined limits. There are many instances 15 where it is desirable to operate one or more valves from a remote station and to have an indication available of the position which the valve occupies at any time. Where the valve and the control-station are far apart, it 20 is advantageous to have the number of wires running between the control-station and the valve as small as possible, not only for the sake of simplifying the system, but in order to reduce the expense of the installation.

25 The object of the present invention is to provide a simple system of control for a motor which shall require only a minimum number of metal conductors between the control and the valve stations, which shall 30 operate with certainty to cause the motor to move a valve or other member in either direction step by step, and which shall indicate back to the control-station the exact position of the valve or other movable member.

35 To the above ends the present invention comprises a novel arrangement and organization of parts to be hereinafter described, and particularly pointed out in the claims.

In the accompanying drawings, Figure 1 40 shows diagrammatically a valve-operating system arranged in accordance with the present invention. Fig. 2 is a detail of an indicator, and Fig. 3 shows an automatic circuit-breaker used in the system.

45 Referring to the drawings, 1 indicates a pipe adapted to be opened and closed by means of a gate-valve 2.

3 is an electric motor having a driving connection with the valve-stem 4. This driving 50 connection may take any suitable form—for example, the connection may consist of worm-gearing 5, one member of which is carried by the armature-shaft and the other member screw-threaded upon the valve-

spindle. At the control-station is a source of 55 electric-current supply illustrated as a three-wire distribution system made up of the conductors L, L', and L''. A double-throw switch 6 is arranged to connect either of the supply-conductors L' and L'' to the conductor 60 7, which forms the sole metallic connection between the control and valve stations. Included in series with the conductor 7 are the coil 8^a of a polarized relay 8 at the control-station, a switch 9 adjacent the 65 valve-operating mechanism and adapted to be actuated by the valve or operating mechanism therefor, and the coil 10 of a polarized relay 11 at the valve-station.

To the movable member 12 of the relay 11 70 is connected the movable member of a double-throw switch 13, which in one position connects conductor 7 to the armature of the motor 3 through the field-winding 14 and in the other position connects this conductor to the motor-armature through the field-winding 15. The arrangement is such 75 that in one position of switch 13 the motor runs in a direction to open the valve, while in the other position of the switch the motor operates to close the valve.

The operation is as follows: In order to open the valve, the switch 6 is moved into the position wherein it connects conductor L' to the conductor 7, and thereupon current 85 flows from supply-conductor L' through conductor 7, through relay 8, through switch 9, through relay 11, to ground. The movable member of the relay 11 is drawn to the left and switch 13 is operated into the position 90 wherein current flows from conductor 7 through the field-winding 14, through the armature of motor, to ground. The motor therefore begins to run and the valve begins to open. After the valve has been opened 95 a predetermined amount a pin 16 on a portion of the valve-operating mechanism strikes the movable member of the switch 9 and interrupts the circuit between the control-station and the valve-station. Both re- 100lays therefore assume their normal positions and the motor comes to rest. The momentum of the motor is, however, sufficient to carry the pin 16 beyond the switch-arm 9, so that this switch is again free to close and the 105 relays are again energized, completing the circuit of the motor as before. The movable member 17 of relay 8 is connected to an in-

indicator 18, which moves step by step as the relay is energized and deenergized, thereby indicating the position which the valve occupies at any instant. As long as the switch 6 remains in the position assumed the circuit of the motor will be automatically opened and closed until the valve has been entirely opened through a series of steps, these steps being shown on the indicator 18. By opening the switch 6 at any time the valve may be stopped in a partially-open position.

In order to close the valve, switch 6 is brought into the position wherein conductor 7 is connected to supply conductor L². Current now flows through the conductor 7 in the opposite direction, and the movable members of the relays are swung to the right instead of to the left, and field-coil 15 instead of coil 14 of the motor is brought into action. The motor now runs in the opposite direction and the valve is closed step by step in the same manner that it was previously opened.

The indicator may take any desired form whereby a step-by-step indication is obtained in synchronism with the step-by-step opening and closing movements of the valve. For example, the indicator may be composed of a movable graduated disk 19, co-operating with a fixed pointer 20, the disk being provided with ratchet-teeth 21 on the periphery. An arm 22, pivoted at the center of the disk, carries at its outer end a pivoted double pawl 23. When the arm is moved in either direction from the central position, one of the pawls engages with teeth 21 and carries the disk with it. The other pawl, however, is held out of engagement with the teeth by means of one of the pins 24. Therefore when the arm is moved in one direction from the normal position the disk is given a clockwise rotation, while upon the other direction of movement of the arm from the central position a counter-clockwise rotation of the disk results.

It will thus be seen that the present invention provides a simple and positive means for opening or closing the valve slowly through a series of steps and making an indication at the distant control-station of the exact position which the valve occupies without the use of more than a single conductor between the valve-station and the control-station.

Although I have described the invention as applied to the operation of valves, it is of course not limited in its application to this particular purpose.

What I claim as new, and desire to secure by Letters Patent of the United States, is—

1. In a system of control, a motor, a reversing-switch, a polarized relay for operating said reversing-switch, a control-station, a single wire conductor and a return connection between said motor and relay and said control-station, and means for causing current

to flow in either direction through said conductor.

2. In a system of control, a motor, a reversing-switch, a control-station, a single wire conductor and a return connection between said motor and relay and said control-station, means at the control-station for causing current to flow in either direction through said conductor, an indicator at the control-station, a second polarized relay for operating said indicator and having a coil in series with said conductor, and means controlled by the motor for momentarily opening the circuit including said conductor after each predetermined number of revolutions of the motor.

3. In a system of control, a motor having independent field-windings for forward and reverse rotation, a control-station, a single conductor connecting said station and said motor, a switch for connecting said conductor to the motor through either field-winding, a polarized relay for operating said switch and having a coil in parallel to the switch, and means at the control-station for producing a flow of current in either direction through said conductor.

4. In a system of control, a motor having independent field-windings for forward and reverse rotation, a control-station, a single conductor connecting said control-station to said motor, a switch for connecting said conductor to the motor through either field-winding, a polarized relay for operating said switch having a coil connected in parallel to said switch, means at the control-station for producing a flow of current in either direction through said conductor, an indicator at the control-station, a second polarized relay for operating said indicator and having a coil in series with said conductor, and means controlled by the motor for momentarily interrupting the circuit through said conductor after each predetermined number of revolutions of the motor.

5. In combination, a movable member, a motor for operating said member, a control-station, a single conductor connecting said motor to said control-station, a reversing-switch between said conductor and the motor, a polarized relay for operating said switch and having a coil connected in parallel to said switch and said motor, a circuit-breaker in series with said conductor, means for momentarily opening said circuit-breaker when the said member reaches predetermined positions, and means at the control-station for causing current to flow in either direction through said conductor.

6. In combination, a movable member, a motor for operating said member, a control-station, a single conductor connecting said motor to said control-station, a reversing-switch between said conductor and the motor, a polarized relay for operating said

switch having a coil connected in parallel to said switch and said motor, a circuit-breaker in series with said conductor, means for momentarily opening said circuit-breaker 5 when the said member reaches predetermined positions, means at the control-station for causing current to flow in either direction through said conductor, an indicator at the control-station, and a polarized relay

for operating said indicator, said latter relay 10 having a coil in series with said conductor.

In witness whereof I have hereunto set my hand this 28th day of May, 1906.

EDWARD M. HEWLETT.
